RIPPLING MACHINE FOR THE TREATMENT
OF TEXTILE MATERIALS

Maurice Alois Soenens, Harelbeke, Belgium, assignor to The Automatic Flax Production Units, Courtrai, Belgium, a Belgian company

Application December 16, 1938, Serial No. 246,078
In Belgium December 31, 1937

3 Claims. (Cl. 130—30)

My present invention relates to rippling machines with combs for the treatment of fibrous, ligneous or other materials, flax for example, preliminarily to other operations of the textile industry, such as for example scutching.

As is well known, before being subjected to scutching, the flax stalks, for example, have to be rippled, an operation which comprises removing from these stalks, by any desired means, the pods containing the seeds.

A certain number of mechanical devices are already known, which have been devised for carrying out this operation and which are known in Flemish by the name of "repelmachinen" and in English by that of "rippling machines."

These known machines substantially comprise a conveyor system and a system of combs. The conveyor seizes the stalks transversely about their middle and feeds them in a layer under the rippling device. The latter comprises one or more movable combs to which are imparted successively a downward movement and a rearward movement and which are then raised again. In descending, the teeth of the combs penetrate the layer then move rearwardly, rendering the stalks more parallel and removing the seed pods which fall, while during the ascent the said teeth are cleaned.

These machines, however, have not a good output in view of the fact that all the movements are abrupt.

The object of the present invention is to provide a very simple and light machine, of considerable robustness and having an almost unlimited output.

For achieving this object, the machine according to the invention is substantially characterised by the cooperation with a conveyor device of any desired type, and on both sides of the latter, of one or more combs which are controlled by a member having a continuous movement of rotation and which are carried by comb-holders pivoted at their upper ends so that each comb, in addition to a downward movement, is simultaneously given a reciprocatory lateral movement and due to this fact, the trajectory of the combs is substantially elliptical.

The accompanying drawings are intended to show by way of examples how the invention may be carried into practice.

Figures 1, 2 and 3 relate to a first form of construction. Figure 1 being a front elevation, Figure 2 a side view and Figure 3 a sectional view.

Figures 4 and 5 are respectively views in ele-

vation and in plan of a device for reducing the thickness of the layer of flax when it is leaving the conveyor.

Figures 6 and 7 show respectively in elevation and in plan the cooperation of the combs in a machine comprising two combs on each side of the conveyor.

Figures 8 and 9 show in detail the combs employed in a machine according to Figures 6 and 7.

Figure 10 shows by way of example a conveyor adapted for use in the machine according to Figures 6 and 7.

Figure 11 shows a constructional modification of the device for reducing the thickness of the layer of fibres.

The machine shown in Figures 1 to 3 substantially comprises two series of rods or teeth 1, 2 forming combs carried by supports 3, 4 secured to two comb-holders 5, 6 engaging crank pins 8, 9 formed respectively on toothed discs 10, 11 meshing with one another and driven by a pinion 12 meshing with the disc 10. The pinion 12 is fixed to a shaft 13 driven by a pulley 14 (Figure 3).

The branch 5 of the comb-holder 3 situated outside the crank pin 8 is articulated on an arm 5² pivoting on a support 5³. In the same manner, the branch 6 of the comb-holder 4 is articulated on an arm 6² pivoting on a support 6³.

The conveyor device for the flax stalks, for example, is formed by a disc 15 fixed to a shaft 16 revolving in supports 17 connected to a cross-member 18 of the frame.

Cooperating with this disc 15 are a certain number of rollers 19 which revolve on spindles 20 carried by plates 21 fixed to a channel iron 22, fixed in turn to a transverse member 23. The rollers 19 are set in rotation by an endless belt 24 which passes over two pulleys 25, 26 and effects the rotation of the disc 15, the pulley 26 being driven by a sprocket wheel 27 which is fast on the same shaft and over which passes a chain 28 driven by a wheel 29 keyed to a shaft 30 also carrying a sprocket wheel 31 actuated by a chain 32 driven by a sprocket wheel 33 fast on a shaft 34 carrying a bevel pinion 35 meshing with a bevel pinion 36 fast on a shaft 37 carrying the disc 11.

Fast on the shaft 38 carrying the pulley 26 and wheel 27 are toothed discs 39, 40 (Figures 4 and 5) intended to act on the flax introduced between the belt 24 and the disc 15 and supported at this place by a plate 41, as will be explained hereinafter.

The shaft 38 drives through a transmission by 55

chain 42 a shaft 43 which in turn drives a shaft 44 through a transmission by chain 45. The shaft 44 drives a shaft 46 through a transmission by chain 47. The shafts 43, 44, 46 each carry 5 pairs of toothed discs 48, 49 and the transmission is so designed that the discs 48, 49 fastened respectively on shafts 43, 44, 46 revolve at increasing speeds.

Under these conditions, the discs 10, 11 being 10 set in rotation in opposite directions by means of the wheel 12, shaft 13 and pulley 14, the crank pins 8, 9 are likewise driven with the rotation of the discs 10, 11, so that due to this movement and due to the fact that they are pivoted at their 15 upper ends, the comb-holders 5, 6 are given a downward movement and at the same time a reciprocatory movement in the directions F_1 and F_2 . The resultant of these two movements is therefore an elliptical movement, the combs always moving away from the conveyor simultaneously and moving towards one another likewise simultaneously.

These combs disposed on both sides of the conveyor have the effect of disentangling and 25 parallelising the flax stalks which is very important for the subsequent treatment and with a view to avoiding waste. In addition, these combs thus moved effect the cleaning of the roots which 30 always contain a rather considerable quantity of earth and weeds, and effect the removal of the seed pods.

The conveying of the flax stalks is effected by 35 means of the endless belt 24 which causes the rotation of the rollers 19 and the disc 15, thus effecting the movement of the stalks which are seized approximately in their middle upon entering the machine, which is effected on a table 48². Said stalks are carried between the belt 24 and the disc 15 and fall on a support 41 where 40 they are subjected to the action of the pairs of toothed discs 39, 40 and 48, 49.

These toothed discs engage the relatively thick 45 layer of fibres and due to the fact that this layer is subjected successively to the action of pairs of toothed discs, the speed of rotation of which progressively increases, the thickness of the layer of fibres is diminished and a thin and uniform layer is obtained which may be introduced directly into a scutching machine.

It should be remarked that in the construction 50 described (Figures 1 to 5), brushes 48¹ are provided at the ends of the trajectories of the combs for cleaning the teeth of the combs and freeing 55 them more particularly of earth or other impurities with which they are charged as they move between the stalks of flax or other material.

Figures 6 to 10 show a constructional modification 60 in which use is made on each side of a conveyor shown in Figure 10 of two combs, each of which describes a trajectory ellipses like the combs 1 and 2 of Figures 1 to 3.

In this construction, discs 49', 50 meshing with 65 one another and rotating in opposite directions are fast on shafts 51, 52.

The discs 49', 50 each carry a crankshaft 53, 54 and each of these shafts has two cranks 55 and 56 on which are engaged comb-holders. Engaging 70 the cranks 55 are comb-holders 57, 57' pivoted together about the top on a pin 58, while engaging the cranks 56 are comb-holders 59, 59' pivoted on a pin 60.

The conveyor (Figure 10) is formed by two end- 75 less belts 61, 62 passing respectively over pulleys

63 and 64 and gripping the stalks between them. A series of small rollers 65, just as in Figure 1, is provided.

As will be readily understood, each of the combs 66, 67 or 66¹, 67¹ situated on the same side of 5 the conveyor is controlled by the discs 49, 50, so as to travel over an elliptical trajectory. The arrangement is, however, such that when one of the combs is nearest the conveyor, the other is farthest away therefrom. Furthermore, the 10 combs 67, 67¹ carried by the comb-holders 57, 57¹ possess teeth 68 close together, serving more particularly for removing the seed pods (Figure 8), whilst the combs 66, 66¹ carried by the comb-holders 59, 59¹ possess teeth 69 spaced further 15 apart and serve more particularly for parallelising the flax stalks.

The machine is completed by brushes 70 for cleaning the teeth of the combs.

As shown in Figure 11, irrespective of the form 20 of construction, it is possible, if desired, to replace the pairs of toothed discs by pairs of rollers 71, 72, 73 which are driven at progressive speeds starting from the conveyor exit.

The invention is therefore principally distinguished by:

1. The drive of the combs which is derived from a continuously rotating member.
2. The disposition of the combs on both sides of 30 the conveyor which imparts to them the following multiple functions:
  - (a) Parallelising the stalks.
  - (b) Cleaning the roots which always contain earth and often weeds.
  - (c) Removal of the seed pods.

The invention thus provides a very simple, very light and very robust machine of practically unlimited output.

This machine may be applied in numerous industries and particularly in all industries where fibrous, ligneous and the like materials have to be rendered quite parallel and cleaned.

What I claim is:

1. In a rippling machine for the treatment of 45 fibrous, ligneous or other materials in combination, means for conveying the materials through the machine, a plurality of pairs of combs adapted to engage the materials, one comb of each pair being mounted on one side of said conveyor and the other comb of each pair being mounted on the other side of said conveyor, means for continuously driving the combs, comb-holders carrying at one of their ends the said combs, the comb-holders being pivoted along their length at 55 their point of support on said driving means and pivoted at their other ends, the other ends of each pair of comb-holders being pivoted one on the other, whereby the combs in addition to their downward movements are given reciprocating lateral movements, the trajectory of the combs being substantially elliptical.

2. In a rippling machine for the treatment of 60 fibrous, ligneous or other materials in combination, means for conveying the materials through the machine, a plurality of pairs of combs adapted to engage the materials, one comb of each pair being mounted on one side of said conveyor and the other comb of each pair being mounted on the other side of said conveyor, means for continuously driving the combs, comb-holders carrying at one of their ends the said combs, the comb-holders being pivoted along their length at their 65 point of support on said driving means and pivoted at their other ends, the points of supports 70

on said driving means being such that when one pair of combs is closest to the conveyor the other pair is farthest away, the other ends of each pair of comb-holders being pivoted one on the other, whereby the combs in addition to their downward movements are given reciprocating lateral movements, the trajectory of the combs being substantially elliptical.

3. In a rippling machine for the treatment of fibrous, ligneous or other materials in combination, means for conveying the materials through the machine, a plurality of pairs of combs adapted to engage the materials, one comb of each pair being mounted on one side of said conveyor and the other comb of each pair being mounted on the other side of said conveyor, means for continu-

ously driving the combs, comb-holders carrying at one of their ends the said combs, the comb-holders being pivoted along their length at their point of support on said driving means and pivoted at their other ends, the points of supports on said driving means being such that when one pair of combs is closest to the conveyor the other pair is farthest away, one pair of combs possessing teeth closer together than the teeth of the other pair of combs, the other ends of each pair of comb-holders being pivoted one on the other, whereby the combs in addition to their downward movements are given reciprocating lateral movements, the trajectory of the combs being substantially elliptical.

MAURICE ALOIS SOENENS.
